Andrew D. Bochner

(57) **CLAIM**

The ornamental design for a display screen with graphical user interface, as shown and described.

DESCRIPTION

FIG. 1 is a front view of a display screen with graphical user interface showing the new design;

FIG. 2 is a front view of another embodiment thereof;

FIG. 3 is a front view of another embodiment thereof;

FIG. 4 is a front view of another embodiment thereof;

FIG. 5 is a front view of another embodiment thereof; and,

FIG. 6 is a front view of another embodiment thereof.

The broken lines showing an electronic device illustrate environmental subject matter, whereas the broken lines showing elements of the graphical user interface illustrate portions of the article. None of the broken lines form part of the claimed design.

1 Claim, 6 Drawing Sheets
